CLAIM

The ornamental design for a luminaire, as shown and described.

DESCRIPTION

FIG. 1 is an upper perspective view of a luminaire according to the invention.

FIG. 2 is a lower perspective view of the luminaire of FIG. 1.

FIG. 3 is a top plan view of the luminaire of FIG. 1.

FIG. 4 is a bottom plan view of the luminaire of FIG. 1.

FIG. 5 is a right side elevational view of the luminaire of FIG. 1.

FIG. 6 is a left side elevational view of the luminaire of FIG. 1.

FIG. 7 is a front elevational view of the luminaire of FIG. 1. FIG. 8 is a rear elevational view of the luminaire of FIG. 1; and,

FIG. 9 is a front elevational view of the luminaire of FIG. 1, positioned against a canopy for installation of the luminaire in the canopy.

The portions in the Figures shown in broken lines are environmental only and form no part of the claimed design.

1 Claim, 7 Drawing Sheets
